ICE GRIPPER

Louis A. Priess, Minneapolis, Minn.

Application November 8, 1943, Serial No. 509,524

2 Claims. (Cl. 36—62)

My present invention relates to improvements in ice grippers applicable in pairs to the soles of shoes to prevent the wearer from slipping when walking on ice, slippery grass, moss and the like.

The objects of this invention are to provide ice grippers that are extremely simple, highly efficient, that can be very quickly and easily applied to a pair of shoes or removed therefrom, that are self-adjustable to shoes of different sizes, and that can be sharpened when dull.

To the above end, generally stated, the invention consists of the novel construction and arrangement of parts hereinafter described and defined in the claims.

In the accompanying drawing, which illustrates the invention, like characters indicate like parts throughout the several views.

Referring to the drawing:

Fig. 1 is a side elevation of one of the improved ice grippers, some parts being broken away and sectioned;

Fig. 2 is a bottom plan view; and

Fig. 3 is a fragmentary view partly in elevation and partly in section taken on the line 3—3 of Fig. 1.

My improved ice gripper is stamped from a single sheet of metal and includes a flat body member 4 having at each of its longitudinal edges a row of depending sharp teeth 5. The ice gripper is removably held on the soles of a shoe with its two rows of teeth 5 extending transversely of said sole by an elastic webbing 6. The end portions of this webbing 6 are extended through slots 7 in the end portions of the body member 4 and secured by staples 8. To completely cover

and hide the ends of the webbing 6, said webbing is first inserted through the slots 7, folded upon itself and then again folded under the body member 4 and covered by the main body portion of said webbing 6.

In applying the ice gripper to a shoe, said shoe is inserted through the loop formed by the webbing 6, while held stretched, with the ice gripper under the sole of the shoe. Obviously, the elastic webbing 6 will adjust itself to shoes of different sizes. The webbing 6 will securely hold the ice gripper in place on the sole of a shoe. When a pair of these ice grippers are applied to the soles of a pair of shoes, they will prevent the wearer from slipping when walking on ice, slippery grass, moss and the like.

What I claim is:

1. In a device of the class described, a flat metal plate having at each of its longitudinal edges a row of depending teeth and also having a transverse slot in each of its end portions, an elastic webbing having its end portions inserted through said slots, folded upon itself and then again folded between itself and the plate, and staples connecting the folded end portions of the webbing outwardly of the plate.

2. In a device of the class described, a flat metal plate having at each of its longitudinal edges a row of depending teeth and also having a transverse slot in each of its end portions, an elastic webbing having its end portions inserted through said slots and folded upon itself and the plate, and fastening means holding the end portions of the webbing attached to the plate.

LOUIS A. PRIESS.
